MACHINE FOR MAKING PIPING, WELTING,
FINISHING STRIPS OR THE LIKE

A. Waldo Rockwood, Winchester, Mass.

Application May 14, 1935, Serial No. 21,419

3 Claims. (Cl. 154—1)

My present invention is a novel and improved machine for use in the manufacture of ornamental finishing strips, piping, welting or the like, and includes a novel method of manufacturing same.

Heretofore in the making of such articles it has been extremely difficult to manufacture and ornament such devices, particularly where contrasting colored strips are used and where composite material including fabric covered by celluloid, Bakelite, lacquer, or similar finishing material is utilized. A similar difficulty arises where leather, particularly patent leather, is employed because of the difficulty in handling the base or body portion of the strip or article to be manufactured and ornamented into a finishing strip for use in welting, piping, or other ornamentation on boots and shoes, clothing, upholstery, and the like.

These finishing strips are frequently made of extremely narrow material and are necessarily manufactured at high speed in order to save expense.

My present invention aims to simplify the difficulties heretofore experienced, and to provide a simple, efficient, and easily operated apparatus and by a novel process.

In carrying out my invention, I provide means which will feed a strip of the base material through the machine and simultaneously apply to the base material an ornamental strip, or stripping, of narrower substance and, preferably, of contrasting color; conduct the narrow and ornamental portion through a mass of liquid adhesives, which is preferably colorless or which may be colored to accentuate the showing of the contrasting ornamental strip; force this adhesive under positive power-driven means so as to maintain a uniform pressure and action, thereby combining the two strips.

Thereupon, I dry the thus-combined members while the adhesive sets and solidifies and becomes sufficiently dry and hard to enable the finished ornamental strip to be wound upon a reel and shipped for use.

I find that it is desirable and important in carrying out the present process, and accordingly I have developed my machine therefor, to utilize a positive feeding means, such for example, as a gear pump which regulates the flow of the liquid adhesive and supplies a substantially uniform and predetermined pressure on the liquid while it is applied to the narrower ornamental strip, as well as while the narrower strip is being applied to the base strip. This method gives positive control, feeding just the right amount of the liquid by regulating the speed of rotation of the gear pump, or its equivalent, and furthermore keeps the liquid in the proper consistency during use.

A further advantage of the positive feeding means, such as the gear pump above referred to, enables me to manufacture the ornamental striping at great speed and with considerable economy, eliminating all necessity of handling, transferring, or the like.

Furthermore, by having a two-part die through which the narrow ornamental strip is drawn to pick up the adhesive supplied thereto under pressure, I can substitute numerous die portions when changing widths, styles, or the like by simply removing the lower portion of the die and substituting a different one. This also enables me to use the same machine for making narrow, single ornamental strips as well as to apply a plurality of narrow strips on the same base, adjusting also the guides for the material being fed both for the base material and for the narrower ornamental strips, or a plurality of the same.

Further novel features, combinations, and advantages will be hereinafter more fully pointed out and claimed.

Referring to the drawings illustrating a preferred embodiment of the present invention,

Fig. 1 is a side view illustrating my apparatus;

Fig. 2 is a plan view of the drying reel, partly broken away;

Fig. 3 is an enlarged view partly in vertical cross-section;

Fig. 4 is a cross-sectional view on the line 4—4 of Fig. 3;

Fig. 5 is an enlarged view partly in cross-section showing the adjustable guides;

Fig. 6 is an enlarged detailed view illustrating the guide adjustment;

Fig. 7 is an enlarged cross-sectional view on the line 7—7 of Fig. 3;

Fig. 8 is a fragmentary plan view showing the machine from the right of Figs. 1 and 3;

Fig. 9 illustrates in fragmentary form the die construction where a single strip, is formed simultaneously;

Fig. 10 is a corresponding fragmentary view illustrating the forming of a plurality of ornamentalations;

Fig. 11 is an enlarged perspective view of the ornamental stripping on a single strip, and

Fig. 12 is an enlarged fragmentary view in perspective of a base with a plurality of ornamental strips applied thereto by my process and with this machine.

Referring to the drawings illustrating a preferred embodiment, I designates a suitable support having journaled bearings for a shaft 2 on which is secured a rotary work wheel 3, said shaft being rotated by a pulley 4 to which is led a belt 5 from any suitable source of power. The top of the standard 1 carries a head 10 provided

with suitable bearings for the axle 12, provided one end with a pulley 14 and on the opposite end with a gear 15, which is adapted to mesh with a corresponding idle gear 16 and constitutes the power-forcing means or pump. Rotation of the pulley 14 through a belt 18 leading around a pulley 19, secured to the shaft 2, imparts rotary action to the gear pump comprised of the members 12 and 16, at the top of the head. The head 10 extends upwardly into an open receptacle 20 in which the adhesive material is supplied and, preferably by inverting a container 21 with the pump portion open and resting on an annular gasket or rubber packing 22. If desired, the inner surface of the top 20 may be threaded to fit the correspondingly threaded exterior of the neck of the container 21 as shown at 23, thus constituting a supply tank for the liquid coating and the adhesive 25.

Extending from the receptacle 20 is a bored passage 26 shown best in dotted lines, Fig. 3, which passage leads to an opening in which the teeth of the gears 12 and 16 mesh, as indicated at 28, and a corresponding delivery passage 29 leads from the opposite portion of the gears 12 and 16, which are rotated in the direction of the arrows into a coating chamber 30 formed in the extension 31 of the head 10 and overhanging the surface of the wheel 3. A removable plate 33 covers the gear wheels 12 and 16 and permits ready removal or access thereto for cleaning or inspection. The member 31 is preferably permanently secured to or is a part of the head 10, as above noted, and has a removable lower portion constituting the changeable die member 35. This interchangeable die member 35 can be attached to the fixed portion 31 by bolts 36, or the like, and has contained therein a lower portion 38, which, combined with the liquid-receiving chamber 30, constitutes a complete liquid receptacle.

My present process contemplates the drawing through this liquid receptacle of the thin or narrow ornamental strip 40 which is coated and entirely surrounded by the liquid adhesive forced from the gear pump through the channel 25 into the chamber 30, the narrower finishing strip 40 being fed therethrough and in contact with the base strip 50 which is to be ornamented and which is fed through on top of the wheel 3.

For this purpose I may form a groove or channel through the upper part 31 of the removable die portion 35, or form such groove as a part of each of the contacting surfaces of the removable die portion 35 and the fixed part 31.

Preferably, however, I use the surface of the fixed die 31 as one wall of the groove through which the ornamental strip 40 is drawn and form one or more grooves in the removable die portion 35 through which the finishing strip or strips 40 may be drawn, see Figs. 7, 9, and 10. Preferably, also, this groove for the strip 40 is formed at an appropriate angle so that the ornamental strip 40 may be drawn from a reel 41, held in a bracket 42 in convenient position, and led through friction rolls 43 (see Fig. 1).

Similarly, the base material 50 is led from a reel 51 on a bracket 52 and around friction rolls 53. Thus, I provide a groove 44 at the entrance end for the ornamental strip 40, a corresponding delivery groove 45 at the opposite portion, the strip 40 feeding therethrough and through the liquid in the chamber 30 and out of the delivery opening 45 on to the surface of the base strip 50, where it is pressed firmly thereon by a rearwardly

extending portion 48 of the fixed die 31, thus being forced into intimate contact with the base 50 and being surrounded by liquid adhesive illustrated in over-drawn size at 49, Fig. 11.

In order to conserve the liquid contained within the diameter 30 and prevent the pressure of the gear pumps 12 and 16 forcing the liquid outwardly through the channel 44, I provide a spring-pressed gate gauge 55 which is moved downwardly on the ornamental strip 40 by the tension of the spring 56 surrounding one or more movable guide pins 57 extending through a boss 58 on the fixed die 31. A by-pass 60 leading from the chamber 30 to the upper bored passage 26 is also provided so that in case the pressure afforded by the gears 12 and 16 forces an excess of liquid into the chamber 30, it may be returned without difficulty or damage.

It is important to provide guiding means both for the base strip 50 and the ornamental strip 40. The guide gauge 55 and groove 44 will ordinarily be sufficient to act as guiding means for the narrow strip 40 and, therefore, I have only provided adjustable guides for the base strip 50 to feed the same in proper alignment under the die 35 so that the ornamental strip 40 will be positioned thereto in proper relationship either centrally or otherwise. When a plurality of strips are fed through, the guiding of the base strip 50 is all that is essential so that it is adjustable relatively with the delivery recess, or recesses, 45 in the die through which the ornamental strip or strips 40 are conducted.

For this purpose I form an extension 70 on the head 10 at the right, viewed in Figs. 1 and 3, and form a tapped recess therein to receive the pivotal guide rod 71 which is fixed thereto and also an open recess to receive one end of a threaded adjusting screw 72, on which are fixed collars 73—73. Depending from the guide rod 71 is a slide 74 having a pair of framewise members 75—75 perforated with slightly larger holes than that of the diameter of the guide rod 71 so that the frame will slide thereover. Depending from the frame 74 are extensions 76—76 carrying a shaft 77 between one of which are adjustably secured two guiding gauges 78—78 which may be moved and secured in any relative spacing position desired by loosening and tightening set screws 79—79, these gauges 78 being preferably rings encircling the shaft 77.

The adjusting screw 72 has a knurled thumb nut 80 on the outer end and is provided with threaded engagement through the frame 74 so that manipulation of the thumb nut 80 will slide the entire frame and adjusted gauges 78—78 in any relative position desired across the face of the work wheel 3, thereby conducting the base strip 50 in desired alignment so that it will register with the ornamental strip 40 when the same is applied thereto and united by the pressure of the extension 48 on the die 31.

While this guiding means for the base 50 in advance of the action of the die is ordinarily sufficient to align the two strips 40 and 50, yet it may be desirable to provide a further guiding means for the strip 50 closely adjacent the point of contact of the two strips 40 and 50. For this purpose I may provide independently adjustable guides as shown in Figs. 4 and 5. These comprise right and left sliding plates 84 and 85 adapted to fit under the die 31, and, if desired, in a groove formed therein closely adjacent the point where the strips 40 and 50 are brought in contact on top of the work wheel 3. These slides are independently ad-

justable toward and from the center and of an equal thickness to that of the strip 50, this adjustment comprising a pair of knurled thumb screws 86 and 87 secured to shafts passing through 5 bored recess in an upstanding part 88 of the slide 84, and 89 of the slide 85, the shafts of each of the adjusting screws 86 and 87 being provided with collars 90-90, respectively, fitting each side of the upstanding lugs 88 and 89 and having the shank 10 portions threaded into tapped recesses in the die 31, as clearly illustrated in Figs. 4 and 5.

If desired, also, I may provide a guide in the form of studs 91-91 secured to the upstanding portions 88 and 89 and sliding in recesses 92-92 15 in the die 31 spaced slightly from the adjusting screws to provide a guide or supporting bearing for the guide plates so that they may be adjusted toward and from each other from time to time as desired during the actual feeding of the strips 20 through the machine to secure the correct alignment.

In Fig. 10, I have illustrated a removable die portion 95 corresponding with the removable portion 35 above described, which has a plurality of recesses 96-96 to receive a plurality of strips 98-98 when it is desired to utilize a plurality of such ornamental strips on a single base part 100, see Fig. 12. In this form, a plurality of strips 98 are fed 25 through the liquid-receiving or coating chamber 30 30, and all the strips are simultaneously pressed upon the base 100 being surrounded by the coating adhesive 49. With the strips 40 and 50 united, or the plurality 98 and 100 pressed together by the action of the die and carried onwardly by the 35 work wheel 3 to the left, viewed in Figs. 1 and 3, the combined material designated in Figs. 1 and 2 as 101 is led around the work wheel 3 and to and around a drying reel, as shown in Figs. 1 and 2. As many turns as may be desired to thoroughly 40 dry the coating material 49 is made so that the drying is insured before the same is led therefrom to be wound on a spool, or the like. This reel comprises a pair of open framework cylinders 103 and 104 mounted on suitable axles 105 and 106 45 respectively, provided with pulleys 107 and 108, respectively, united by a belt 110 which, in turn, receives rotation in timed relation with the feed action by a belt 112 connecting the reel 104 with the properly proportioned pulley 114 on the 50 shaft 2.

A combined ornamented strip may be led into a receptacle 115 or wound directly upon a spool for shipment, as desired.

The entire operation is automatic, and once the 55 adjustments are set for the desired alignment of the ornamental strip 49 and the base 50, or a plurality of ornamentations 98 on the base strip 100, the machine operates continuously and automatically, requiring only replacement of the supply 60 reels 41 and 51 and the liquid container 21.

While I have shown, and prefer to utilize, a positive liquid-forcing means such as the gear pump 12 and 16, I may utilize a substantial height or head for the liquid solution 25 but as this might 65 vary considerably whereas the gear pump is positive, readily adjusted and controlled, imparting uniform pressure to force the liquid solution into and onto the stripping for the ornamentation and uniting thereof, I much prefer the gear pump construction. The most important feature is the 70 positive forcing of this liquid adhesive and solu-

tion, enabling me to utilize any liquid or plastic solution with a wide range of consistency, i. e. extremely liquid, as mobile as water, or merely plastic of the consistency of cold molasses, thus giving me a wide range of material for the adhesive solution 25.

Furthermore, this solution may be either colorless or may be tinted or shaded, or otherwise colored, to aid in the ornamentation desired on the completed finishing strip 101. This also enables me to utilize a wide range of designs as well as ornamentations and material, permitting me to follow and initiate the rapidly changing styles and demands on finishing, piping, and welting strips of this kind.

I can readily change the solution by the mere shifting of the container 21 when it is desired to employ the leather base 50, for example, if a different solution is desired on the same, some leathers being extremely greasy and repellent to 20 an adhesive which would be entirely satisfactory on a strip built up of textile material and Pyroxylin, as is ordinarily employed for the base strips 50 and 100.

If desired, also, I may utilize a plastic which requires some degree of heat to render it suitable for application, the gear pump affording ample, positive, and power application to force the same into the die and onto the stripping material.

As shown in Fig. 3, I have provided a valve 120 25 on the by-pass in order to regulate and control the pressure built up by the gear pump. This also is useful where the plastic material utilized may vary in consistency.

I claim:

1. Apparatus of the kind described adapted to simultaneously feed material to be ornamented and the ornamentation therefor and apply the ornamentation thereto, comprising a movable work-wheel, a fixed die containing adhesive solution under pressure, and means to guide the ornamenting material through said die and means to apply the same to the material to be ornamented, in combination with adjustable guiding means to effect alignment between the material being ornamented and the ornamentation applied thereto.

2. Apparatus of the kind described adapted to simultaneously feed material to be ornamented and the ornamentation therefor and apply the ornamentation thereto, comprising a movable work-wheel, a fixed die containing adhesive solution under pressure, and means to guide the ornamenting material through said die and means to apply the same to the material to be ornamented, in combination with a yielding gate guiding the material to the die and preventing waste of adhesive under pressure.

3. Apparatus of the kind described adapted to simultaneously feed material to be ornamented and the ornamentation therefor and apply the ornamentation thereto, comprising a movable work-wheel, a fixed die containing adhesive solution under pressure, and means to guide the ornamenting material through said die and means to apply the same to the material to be ornamented, in combination with positive pumping means to control the pressure upon the ornamenting solution.

A. WALDO ROCKWOOD.
